UNITED STATES PATENT OFFICE.

JACOB R. SENSIBAR, OF CHICAGO, ILLINOIS.

PUMP CONNECTION.

Application filed April 16, 1925. Serial No. 23,736.

This invention relates to pump connections and the like.

The primary object of this invention is to provide a ready means for connecting and disconnecting the suction pipe on sand barges and the like so that the suction pipe may be readily disconnected at the side of the boat and placed upon the deck, thereby leaving the side of the vessel smooth and without a pipe extending permanently from the side of the vessel as has sometimes been done.

Another object is to provide a ready seal between the suction pipe and the vessel which is easy to make and kept in repair.

These and other objects are accomplished by the invention which is fully described in the following specification and shown in the accompanying drawings, in which:

Figure 1 is a partial side elevation of the forward end of a boat embodying the invention;

Fig. 2 is an enlarged partial section on the line 2—2 of Fig. 1;

Fig. 3 is a similar section on the line 3—3 of Fig. 1;

Fig. 4 is a rear elevation looking outwardly of the crane for raising and lowering the suction pipe and for swinging it inwardly toward the deck; and

Fig. 5 is a top plan view of the same.

The embodiment illustrated comprises a boat having a hull 10 within which is mounted upon a suitable bar 11 a centrifugal pump 12. The intake to this pump consists of an intake pipe 13 which connects through a gate valve 14 with an opening 15 through the side of the hull below the water line as is shown in Fig. 1.

A track 16 having flanged edges as is shown in Fig. 3, lying on each side of the opening 15 and extends upwardly and forwardly from this opening to a convenient point on the deck above the hull 10. A plate 17 having grooved edges slides within the track 16 as is shown in Fig. 3, and carries a pulley 18 over which runs a lifting rope 19 for raising and lowering the plate 17 as will later be described.

A crane 20 is mounted upon the forward deck and adapted to swing above a vertical pivot 21. This crane carries a member 22 which is pivotally mounted upon a vertical pivot pin 23 so as to permit the member 22 to move into alignment with the hull 10 of the vessel as the crane is moved outwardly to the position as shown in Figs. 4 and 5. Sections

of track 16^a are carried by the member 22 and in the position shown are in alignment with the track 16 on the side of the vessel.

The rope 19 after passing around the sheave 18, as shown in Fig. 1, passes around the sheave 24 on the upper portion of the member 22, thence around the sheaves 25 and 26 and down to a hoisting drum (not shown).

The suction elbow 27 is journaled within the plate 17 as shown in Fig. 3, and is retained therein by means of two half rings 28 which are held by means of studs 29, thereby permitting the elbow 27 to swing as the suction pipe is being raised and lowered. Two or more sections of suction pipes 30 and 31 are flexibly connected to the elbow by means of rubber tubing 32 and 33, the lower section of the suction pipe carrying a suitable suction nozzle 34. The suction pipe is carried by means of slings 35 and 36 which are swung from ropes 37 and 38, running over suitable blocks on the davits 39 and 40 so that as the elbow 27 is raised and lowered by means of the rope 19, the section line is simultaneously raised and lowered by means of the ropes 37 and 38 running over the blocks on the davits 39 and 40.

From the foregoing it will be understood that with the pump going and the parts in the position as shown in Fig. 1, as will be the case during pumping, to disconnect the suction line and bring it over the side of the vessel, the operator first closes the valve 14 then simultaneously lifts the suction line by means of the ropes 19, 37 and 38, thereby raising the suction line until the pipes 30 and 31 lie sufficiently horizontal and the plate 17 drawn completely clear of the track 16 and into the track 16^a. The member 22 can then be swung back over the deck of the vessel, the rope 19 being held locked in this raised position. At the same time the davits 39 and 40 permit the suction pipe to be raised so as to clear the top of the hull so that this suction pipe can be laid full length upon the deck. Thus it will be seen that a very convenient means is provided for completely disconnecting the suction line from the side of the vessel so that there is no longer any danger of the vessel striking an object which will break and injure the suction line.

At the same time the entire suction line, lying as it does below the water line, forms a convenient water seal, the suction of the pump in operation tending to draw all of

the parts toward the hull, thereby greatly diminishing the amount of water which may leak in around the plate 17.

The davits 39 and 40 have substantially the same radius as the crane 20 so that by properly placing the ropes 37 and 38 upon the suction pipe, the crane and davits will swing together to move the suction pipe on or off the boat.

10 While I have shown and described but a single embodiment of this invention, it is to be understood that it is capable of many modifications. Changes therefore in the construction and arrangement may be made which do not depart from the spirit and scope of the invention as disclosed in the appended claims.

I claim:

1. In a boat and the like, a hull, a pump within the hull, a hole in the side of said hull, a pipe connecting said pump and hole, a suction pipe for said pump, a track on the side of said hull, a plate slideable in said track, an elbow swivelly connected to said plate, said elbow being connected to said pipe, a crane mounted above the top edge of the hull and swingable inwardly about a vertical axis, a member carried by said crane and swingable about a vertical axis thereon, and a second track on said member movable into alignment with the track on the side of the hull, means for raising said plate to said second track, whereby said plate can be swung in towards the deck.

2. In a boat and the like, a hull, a pump within the hull, a hole in the side of said hull, a pipe connecting said pump and hole, a suction pipe for said pump, a track on the side of said hull, a plate slideable in said track, an elbow hingedly connected to said plate, said elbow being connected to said pipe, a crane mounted above the top edge of the hull and swingable inwardly about a vertical axis, a member carried by said crane and swingable about a vertical axis thereon, a second track on said member movable into alignment with

the track on the side of the hull, means for raising said plate to said second track, whereby said plate can be swung in towards the deck, and means on said crane for raising and lowering said plate.

3. In a boat and the like, a hull, a pump within the hull, a hole in the side of said hull, a pipe connecting said pump and hole, a suction pipe for said pump, a track on the side of said hull, a plate slideable in said track, an elbow hingedly connected to said plate, said elbow being connected to said pipe, a crane mounted above the top edge of the hull and swingable inwardly about a vertical axis, a member carried by said crane and swingable about a vertical axis thereon, a second track on said member movable into alignment with the track on the side of the hull, means for raising said plate to said second track, whereby said plate can be swung in towards the deck, and means for raising and lowering the outer end of the suction pipe.

4. In a boat and the like, a hull, a pump within the hull, a hole in the side of said hull, a pipe connecting said pump and hole, a suction pipe for said pump, a track on the side of said hull, a plate slideable in said track, an elbow flexibly connected to said plate, said elbow being connected to said pipe, a crane mounted above the top edge of the hull and swingable inwardly about a vertical axis, a member carried by said crane and swingable about a vertical axis thereon, a second track on said member movable into alignment with the track on the side of the hull, means for raising said plate to said second track, whereby said plate can be swung in towards the deck, and davits for raising and lowering the outer end of said pipe, the radii of said davits and crane being substantially the same so that said davits will swing inwardly and outwardly with said crane.

In testimony whereof I have hereunto set my hand this 26th day of January, 1925.

JACOB R. SENSBAR.
